Primary Examiner — Jennifer L Watkins*Assistant Examiner* — Christine Tucci(74) *Attorney, Agent, or Firm* — GrayRobinson, P.A.(57) **CLAIM**

The ornamental design for a sports bra as shown and described.

DESCRIPTION

FIG. 1 is a front isometric view of a sports bra showing my new design;

FIG. 2 is a front elevational view thereof;

FIG. 3 is a rear elevational view thereof;

FIG. 4 is a bottom isometric view thereof;

FIG. 5 is a top isometric view thereof; and,

FIG. 6 is a front view thereof in an open position showing the inside of the sports bra.
 The broken line show portions of the article that form no art of the claim.**1 Claim, 5 Drawing Sheets**FIG. 1

FIG. 2

FIG. 3

FIG. 4
